(57) **CLAIM**

The ornamental design for a monitor, as shown and described.

DESCRIPTION

FIG. 1 is a front left perspective view of a monitor according to an embodiment of the present invention.

FIG. 2 is a back right perspective view of the monitor of FIG. 1.

FIG. 3 is a front view of the monitor of FIG. 1.

FIG. 4 is a back view of the monitor of FIG. 1.

FIG. 5 is a left side view of the monitor of FIG. 1.

FIG. 6 is a right side view of the monitor of FIG. 1.

FIG. 7 is a top view of the monitor of FIG. 1.

FIG. 8 is bottom view for the monitor of FIG. 1.

FIG. 9 is a front left perspective view of the monitor according to a second embodiment of the present invention.

FIG. 10 is a back right perspective view of the monitor of FIG. 9.

FIG. 11 is a front view of the monitor of FIG. 9.

FIG. 12 is a back view of the monitor of FIG. 9.

FIG. 13 is a left side view of the monitor of FIG. 9.

FIG. 14 is a right side view of the monitor of FIG. 9.

FIG. 15 is a top view of the monitor of FIG. 9; and,

FIG. 16 is a bottom view of the monitor of FIG. 9.

The broken lines in FIGS. 1-16 are included for the purpose of illustrating environmental structure and form no part of the claimed design.

In FIGS. 9-16, the portions between the pairs of closely adjacent, long dash-short dash-long dash broken lines are broken away to indicate no particular length of the display of the monitor, and such pairs of long dash-short dash-long dash broken lines themselves form no part of the claimed design. The portions that may be visible between the long dash-short dash-long dash broken lines have been removed for clarity.
